Primary Examiner — Patricia Palasik*(74) Attorney, Agent, or Firm* — Smith Moore Leatherwood LLP; Thomas W. Epting**CLAIM**

(57) The ornamental design for a wood splitter rack, as shown and described.

DESCRIPTION

FIG. 1 is a perspective view of an embodiment of a wood splitter rack showing my new design;
 FIG. 2 is another perspective view thereof;
 FIG. 3 is a front end elevational view thereof;
 FIG. 4 is a rear end elevational view thereof;
 FIG. 5 is a left side elevational view thereof;
 FIG. 6 is a right side elevational view thereof;
 FIG. 7 is a top plan view thereof; and,
 FIG. 8 is a bottom plan view thereof. The broken lines shown in the drawings are for environmental purposes only and form no part of the claimed design.
